UNITED STATES PATENT OFFICE.

LOUISE H. BOCH, OF CHICAGO, ILLINOIS.

DESIGN FOR A CARRIER FOR VALUABLES.

46,081.

Specification for Design.

Patented July 14, 1914.

Application filed September 2, 1913. Serial No. 787,812. Term of patent 14 years.

To all whom it may concern:

Be it known that I, LOUISE H. BOCH, a citizen of the United States, residing at Chicago, in the county of Cook and State of Illinois, have invented a new, original, and ornamental Design for a Carrier for Valuables, of which the following is a specification, reference being had to the accompanying drawing, forming a part thereof, and in which—

The reference letter I indicates a shaped pocket having a flap or closure portion K. The portions I and K are provided with securing devices L. There are two shaped pockets I which are connected at each end by spaced straps E, E. The straps between two of the ends are divided and provided with a loop or bail F, crossed by bars or pins G to provide a securing device for the free ends of the straps. The shaped pockets are semi-circular with their ends separated and connected by two parallel spaced straps.

I claim:—

The ornamental design for a carrier for valuables, as shown and described.
